UNITED STATES PATENT OFFICE.

BOYD W. DYSART, OF LOS ANGELES, CALIFORNIA.

AIR-SHIP.

939,483.

Specification of Letters Patent.

Patented Nov. 9, 1909.

Application filed August 24, 1908. Serial No. 450,104.

To all whom it may concern:

Be it known that I, BOYD W. DYSART, a citizen of the United States, residing at Los Angeles, in the county of Los Angeles and State of California, have invented a new and useful Air-Ship, of which the following is the specification.

This invention relates to air ships and one of the main objects of the invention is to provide an air ship having a greater buoyancy than those provided with flat surface aeroplanes, whereby the ship is adapted to navigate in a strong wind. One or more drums are employed which rotate in a substantially horizontal plane, and to the outer surface of the drums spiral wings are attached, which, as the cylinders revolve, screw the ship through the air. The rotating drums or cylinders steady the ship by the wind passing through them and also by the wind striking the convex sides of the cylinder. The latter action serves to equalize the up and down pressures.

Vertical and horizontal rudders are arranged inside of the drums with the intention that the steering will be greatly facilitated. Accommodations for the passengers are provided in the interior of the drums and thus greater safety is afforded them, not only when the ship is traveling, but also in alighting. This is by reason of the drums revolving in opposite directions which reverse movement gives an automatic balance both laterally and longitudinally, whereby it is intended that a slow and steady descent may be made in safety. By reason of the passengers being carried within the drums they are not exposed to the discomforts of storms through which they may pass as the cylinders act as houses to protect the passengers from the elements. As it is expected that greater buoyancy will be obtained by this construction it is possible to use heavier and more substantial material than in air ships which depend for their buoyancy on flat aero-planes, and are thus of less buoyancy. The buoyancy of this cylindrical construction is increased by reason of the inner faces of the upper halves of the cylinders acting as aero-planes, and also the outer surfaces of their lower halves acting as aero-planes. Buoyancy is further afforded by the forward rudder which is mounted in the forward cylinder and pivoted to swing in a vertical plane.

Economy and utility are obtained by the use of platforms swinging in the drums. These platforms also act as aero-planes and thereby further increase the buoyancy. An air ship is thus produced having a great aero-plane surface arranged in the most condensed manner. Its supporting buoyancy should be much more than the dirigible balloon or any form of flat surface aero-plane.

Referring to the drawings:—Figure 1 is a vertical section taken longitudinally through the air ship. Fig. 2 is a plan view of the complete ship. Fig. 3 is a section on line x^3-x^3 Fig. 1. Fig. 4 is a section on line x^4-x^4 Fig. 1.

The ship comprises a forward drum 1 adapted to rotate in one direction, and an after drum 2 adapted to rotate in the opposite direction. Each drum has on its surface a series of wings or blades 3, those on the forward drum 1 being inclined in one direction, and those on the after drum being inclined in the opposite direction, the inclination of both sets of wings being such that as the cylinders revolve in opposite directions the ship will be propelled forward. Each drum is braced at each end by cross arms 4 which extend to hubs 5. Extending axially through both drums is a shaft 6. In the forward drum 1, a sleeve 7 is rotatably mounted on the shaft 6, and the hubs 5 of the forward drum 1 are attached to the sleeve 7. In the after drum 2, hubs 5 are attached directly to the shaft 6.

In the forward drum a platform 8 is hung by arms 9 from hubs 10 on the sleeve 7. An engine 11 is mounted on the deck 8, and is connected by a chain 12 with a sprocket 13 on the sleeve 7 so that as the engine operates it rotates the sleeve 7, and as the drum 1 is rigid with the sleeve it is also rotated.

In the after drum 2 a similar platform 14 is suspended by arms 15 from hubs 16 on shaft 6 and an engine 17 is connected by a chain 18 with a sprocket 19 on shaft 6 so that as engine 17 operates it drives shaft 6 and rotates the after drum 2. The engines are so placed and geared to their respective driven elements that the forward drum 1 and after drum 2 are driven in opposite directions.

Arms 20 extend from the forward hub 10 in the forward drum 1, and support a forward horizontal rudder 21 the rear end of which is connected by a cable 22 with a steering wheel 23 arranged near the deck 8 so

that by operating steering wheel 23, the rudder 21 may be adjusted to various angular positions.

In the after drum 2 a vertical rudder 24 is pivoted to the vertical arm 25 and is operated by a cable 26 connected with the wheel 27. The forward horizontal rudder 21 acts as an aero-plane but it is intended primarily to act as a rudder to vary the horizontal elevations of the air ship. The rear vertical rudder 24 is intended to act in steering the air ship to port or starboard or to hold it in a straight course. A pair of legs 28 are provided at the forward end and project down from the hub 29. Legs 28 are braced by braces 31. A similar set of legs are provided at the after end of the ship. 32 is an auxiliary aeroplane.

It is essential to the present invention that the cylinders which present the aeroplane surface should have closed walls to enable them to act as aeroplanes and that the forward and rear ends of said cylinders should be open to enable the air to pass into and out of said cylinders. For the same reason it is essential that the space at the front and rear of the cylinder or of the plurality of cylinders should be clear and unobstructed so that the air can pass freely to or from the cylinders.

What I claim is:—

1. In an air ship, an elongated, horizontal cylinder having closed side walls and open ends, spiral blades on the outer surface of the cylinder forming a revolving aeroplane, and means for rotating the cylinder, the space at the front and at the rear of the cylinder being clear of obstructions to permit of the passage of air through and out of the cylinder.

2. In an air ship, a plurality of elongated, horizontal concentric cylinders each having closed side walls and open ends, spiral blades on the outer surface of the cylinders, and means for rotating the cylinders in opposite directions, the space at the front and at the rear of the plurality of cylinders being clear of obstructions to permit of the passage of air through and out of the cylinders.

3. In an air ship, a plurality of elongated, horizontal concentric cylinders each having closed side walls and open ends, spiral blades on the outer surface of the cylinders, and means for rotating the cylinders in opposite directions, a shaft extending through both cylinders, arms securing one cylinder to said shaft, a sleeve on said shaft and arms securing the other cylinder to said sleeve, the

space at the front end and at the rear of the plurality of cylinders being clear of obstructions to permit of the passage of air through and out of the cylinders.

4. In an air ship, a plurality of cylinders, a shaft extending through the cylinders, a sleeve on the shaft, arms projecting from said sleeve and supporting the forward cylinder, arms projecting from said shaft and supporting the after cylinder, platforms suspended inside the cylinders, and engines on the platforms connected respectively with said sleeve and shaft for driving the same.

5. In an air ship, a plurality of cylinders, a shaft extending through the cylinders, a sleeve on the shaft, arms projecting from said sleeve and supporting the forward cylinder, arms projecting from said shaft and supporting the after cylinder, platforms suspended inside the cylinders, and engines on the platforms connected respectively with said sleeve and shaft for driving the same, a horizontal rudder in the forward cylinder, and a vertical rudder in the after cylinder.

6. In an air ship, a plurality of cylinders, a shaft extending through the cylinders, a sleeve on the shaft, arms projecting from said sleeve and supporting the forward cylinder, arms projecting from said shaft and supporting the after cylinder, platforms suspended inside the cylinders, and engines on the platforms connected respectively with said sleeve and shaft for driving the same, a horizontal rudder in the forward cylinder, and a vertical rudder in the after cylinder.

7. In an air ship, a plurality of cylinders, a shaft extending through the cylinders, a sleeve on the shaft, arms projecting from said sleeve and supporting the forward cylinder, arms projecting from said shaft and supporting the after cylinder, platforms suspended inside the cylinders, and engines on the platforms connected respectively with said sleeve and shaft for driving the same, a horizontal rudder in the forward cylinder, and a vertical rudder in the after cylinder, and legs in front of the forward cylinder and aft of the after cylinder.

In testimony whereof, I have hereunto set my hand at Los Angeles, California, this 17th day of August, 1908.

BOYD W. DYSART.
